UNITED STATES PATENT OFFICE.

CABEL B. HOPKINS, OF PAYNE'S DEPOT, KENTUCKY.

AUTOMATIC MONEY-CHANGER.

SPECIFICATION forming part of Letters Patent No. 288,942, dated November 20, 1883.

Application filed October 24, 1883. (No model.)

To all whom it may concern:

Be it known that I, CABEL B. HOPKINS, of Payne's Depot, in the county of Scott and State of Kentucky, have invented certain new and useful Improvements in Automatic Money-Changers; and I do hereby declare that the following is a full, clear, and exact description thereof, reference being had to the accompanying drawings, in which—

10 Figure 1 shows a plan view of my money-changer with a portion of the top plate removed to show the operative parts beneath more clearly; Fig. 2, a view in front elevation of a section on line $x-x$ of Fig. 1; Fig. 3, a detail plan view of one of the single-coin-discharging devices with the coin-holding tube and a portion of the plate covering the slide removed; Fig. 4, a similar view of the discharging device adapted for use where one or 20 two coins are to be discharged at will from one tube; Fig. 5, a detail sectional view of the same; Fig. 6, a detail plan view of the bottom plate, upon which the discharge-slides reciprocate.

25 The object of my invention is to provide an improved money-changing apparatus adapted not only to deliver coins of different denominations separately, but also to deliver at one time and upon the movement of a single lever or other actuating device any desired combination of the different coins necessary to make up any desired amount of change; and to this end it consists in the construction, arrangement, and combination of parts, as hereinafter described, and more specifically pointed out in the claims.

30 In the drawings, A designates the box or casing of my apparatus. Said casing can be made of wood, metal, or other material, as desired. The top or cover B is preferably made of glass; but I do not, of course, limit myself to the use of that material. Suitably supported within this box is the horizontal partition C, upon or from which are supported 35 the main portions of my apparatus. As shown, the partition C does not extend to the front wall of the casing. Supported upon the partition, and extending across it from side to side, is the plate D, provided, as shown, with its front edge cut away, so as to form a series of U-shaped recesses of different sizes and depth, as and for the purpose hereinafter to be described.

This plate is attached to the partition C by means of legs e e, which support it at some distance above the latter. Instead of using 55 the legs, as shown, the ends of the plate could be bent down and attached to the partition, so as to serve as supports for the plate. Below recesses in the edge of said plate an opening is cut through the partition. Instead of 60 an opening extending the length of the series of recesses, with or without the cross-piece, as shown, a series of openings could be made, one for and below each recess. As shown, there are six of these recesses in plate D. The 65 recess d is to be of such a size as to allow a cent to drop freely through it, the rear end of said recess being curved in a semicircle of a radius a little larger than that of the circumference of such coin. The recesses $d^1 d^2 d^3 d^4 d^5$ 70 are similarly constructed, but of different sizes and depths, to allow the passage of five, ten, twenty-five, and fifty cent and dollar pieces, respectively, with their faces horizontal or parallel to face of the plate. Above each recess 75 is a plate, E, supported above plate D upon distance pieces or strips e e, resting on the latter plate. These distance-pieces are to be of such a thickness for most of the series of plates E E that the one over any particular recess will be 80 raised above plate D a distance a little more than the thickness of the particular coin which the recess is adapted to admit the passage of. Over the one and ten cent recesses, however, the plates E E are to be supported at a distance slightly greater than the thickness of 85 two of such coins, respectively. Each plate is provided with a circular opening or passage, E', of a size a little larger than the respective coin designed to be dropped therethrough. 90 The rear end of each recess extends only to a point about below the center of such opening, as shown in the drawings. Around the edge of each opening the plate is cut away above, so as to form an annular recess, F, in which 95 fits the lower end of a tube, G, preferably of glass. These tubes are, as shown, adapted to receive coins of different denominations, but are preferably of the same length, though this, of course, is not essential. Between each plate 100 E and plate D, and guided by the distance-pieces e e, move the slides H, provided with circular openings h, corresponding in size to the opening in the plate above each slide. Be-

tween each of the plates supporting the lower ends of the one and ten cent tubes, respectively, and the plate D there is also a second similar slide, H', placed above the slide H.

5 In the case of the single discharge-slides, each one is made to fit the passage between plates D and E closely, and of a thickness equal to or slightly greater than the thickness of the respective coins to be discharged by them.

10 Each of the two slides moving in the passage below the one and ten cent coin holders or tubes is of a thickness equal to or slightly greater than the thickness of the respective coins. With this construction a coin may

15 rest in the opening in either slide, and yet the slides will be able to move independently of each other. The single discharge-slides for the five, twenty-five, and fifty cent coins and for the dollars are made alike in form,

20 though differing in size and thickness. Each of said slides is provided with an arm, h', extending rearward through and guided in an opening, h², in the upper end of a standard, h³, attached to the partition and situated

25 just back of plate D. These standards also serve as stops to limit the backward movement of the slide, as shown. At the desired limit of such movement the rear edge of the main portion of the slide proper strikes against

30 these lugs. The rear ends of the slide-arms are guided in similar openings, i, on similar standards, I I. A spring, K, attached at one end to the standards h³, and at the other attached to or engaging with the arm h', pref-

35 erably at a point between the standards h³ and I, is provided for each slide, so as to keep such slide normally in the position shown in Fig. 1 at the limit of its backward throw, so that it will be situated with its opening be-

40 low and coinciding with the bore of the coin-holding tube above. Each of the single slides referred to is provided with a lip, L, extending backward and inward toward the center of the opening through the slide, from the

45 front edge of such opening. The slides for the one and ten cent coin tubes or holders are, as indicated above, double ones. Of these the slide H, or the lower one, is constructed like those already described, and is provided with

50 a similar lip, L. The upper slide, H', has no such lip, but is otherwise similar to slide H. Each of these slides is, like the others already described, provided with an arm extending rearward, and similarly guided be-

55 tween lugs on standards. A retracting-spring, K, is also provided for each slide-arm. The two springs are on opposite sides of the arms, and while at one end they are attached to or bear against the same standard just back

60 of the plate D, at their other ends they are inserted in ears or lugs k and k', respectively, one extending outward from one side of one slide-arm and the other from the opposite side of the other arm, as shown in the drawings,

65 Fig. 4. The arm attached to the upper slide is provided with a pin, l, which extends downward through a slot, l', in the lower arm. This

slot is so situated with respect to the pin that when both slides and arms are thrown back to the limit of their movement by their respective springs the pin rests against the front end of the slot. Said slot is of such length that the lower slide can be drawn forward far enough to discharge the coin held in its opening or passage without the rear end of the slot engaging and moving forward the pin attached to the arm of the upper slide. With this construction, then, while the lower slide can be moved forward to discharge a single coin, if the upper slide be pulled forward it will move the lower one with it, as its pin normally rests at or near the front end of slot l' in the lower arm, and two coins held in the openings in the slides will be discharged down through recess in plate D and into the delivery-hopper M, below the opening or openings through the partition C. This hopper at its upper and rear edge extends from side to side of the casing, so as to be under the whole series of coin-discharge recesses in plate D. It stands downward at a considerable angle, so that the coins falling into it will be sure to slide down to its reduced discharge end or spout S. From the point where the reduction in width of the hopper or chute begins its edges are turned up to properly guide the coins down toward the discharge-spout and prevent them from sliding off the sides of said chute, which is to be supported in any desired way, either from the bottom of the partition plate or board C or from the inner sides of the box or casing. In the space between the front edge of the partition and the front board of the casing is the horizontal shaft or rod N, supported at either end in the sides of the casing and at or near its middle point in a bracket, O, extending out from the partition-board. Instead of such arrangement, the rod could be supported entirely from the partition-board in a series of bracket-arms extending forward therefrom. Upon this, and between the arms, are pivoted the elbow-levers P P and P' P', twenty-two in number, which have hubs or pivotal sleeves o o, between which are washers o' o'. The levers P' P' have longer arms than the others, and their horizontal arms p' p' are curved downward, so as to pass under and be out of the way of the keys or finger-plates p p on the ends of the horizontal arms p² p² of the levers P P, and at their outer ends, which are beyond and below the ends of arms p² p², they are provided with a series of keys or finger-pieces, p³ p³. The upright arms q' q' of levers P' P' are preferably somewhat longer than the corresponding arms, q q, of levers P P, so that the upper ends of the arms of all the levers will have substantially the same amount of throw. The keys or plates on levers P P are numbered 1, 10, 20, 30, 40, 50, 60, 70, 80, 90, and 100, to represent that number of cents, and the keys or plates on levers P' P' are correspondingly numbered 2, 5, 15, 25, 35, 45, 55, 65, 75, 85, and 95. The front edges of the delivery-slides described above project be-

yond the front edges of plates D and E, and are provided with a series of holes, *m m*. The upright arms of the levers P P and P' P' are also provided with a series of small holes, *n n*.
 5 Instead of the holes, in both cases series of pins may be employed. The levers numbered 5, 25, 50, and 100 have their upright arms connected with the delivery-slides of the tubes containing the five, twenty-five, and fifty cent 10 and one-dollar holder tubes, respectively, by means of a flexible wire, cord, or chain attached at one end to the lever and at the other to the edge of slide, the holes in lever and slide facilitating such connection. The levers numbered 1 and 10 have their arms similarly 15 connected with the lower slides beneath the one and ten cent holders, respectively. The lever marked 2 is connected with the upper delivery-slide of the one-cent holder, and lever numbered 20 is similarly connected with the upper discharging or delivery slide of the ten-cent holder. If, then, the lever marked 2 be actuated by depressing the key, both slides below the one-cent tube will be pulled forward, 25 because any forward movement of the upper slide must cause a corresponding movement of the lower one also, as is obvious from the description of the construction of the slides and arms, as set forth hereinbefore. Likewise 30 when the key marked 20 is depressed both slides under the ten-cent holder will be drawn forward, delivering two ten-cent pieces. The other levers are connected as follows with the coin-delivery slides. Lever 15 is connected with 35 lower ten-cent and the five-cent slides; lever 30 with twenty-five and five cent slides; lever 35 with twenty-five and lower ten cent slides; lever 40 with twenty-five, ten, and five cent slides; lever 45 with upper ten and twenty-five cent 40 slides; lever 55 with fifty and five cent slides; lever 60 with fifty and lower ten cent slides; lever 65 with fifty, lower ten, and five cent slides; lever 70 with fifty and upper ten cent slides; lever 75 with fifty and twenty-five cent 45 slides; lever 80 with fifty, twenty-five, and five cent slides; lever 85 with fifty, twenty-five, and ten cent slides; lever 90 with fifty, twenty-five, lower ten, and five cent slides; lever 95 with fifty, twenty-five, and upper ten cent 50 slides. A rod, T, extends across the box in front of the upright lever-arms, or between them and the casing. This rod at its ends is bent downward, and the lower ends of the downwardly-extending portions *t* are pivoted 55 on lugs or pins *t' t'*. The rod T beyond the end of the series of lever-arms carries a horizontal fixed arm, U, carrying on its rear end, which extends over the front edge of the partition-board C, a pivoted pawl, V, which, 60 when the rod T and arm U are pulled forward by any one of the lever-arms as the lever is actuated to discharge change from the coin-holder, engages on a spring striker-arm, W, attached to or supported on board C, and 65 causes it to strike a bell, X, suitably supported within the box. A spring, Y, is provided for pulling the rod back to its normal position

after the lever has been released. The rod, besides carrying the bell-striker-actuating pawl, will also obviously serve to keep the upright lever-arms, and so the keys on the horizontal arms, in line. 70

I contemplate providing a cover for the tops of the coin-holding tubes, as indicated in dotted lines in Fig. 1. This cover is provided 75 with a series of slots for the admission of coin to the several tubes.

The operation of my apparatus is as follows: When coin has been put in place in the tubes provided therefor, the lower coin rests in the 80 circular opening in the slide and upon the lower plate, D, and the lug attached to the slide within the opening. If the slide is now drawn out, the coin is carried along, with its front edge still resting on the lug, until its rear edge 85 passes off of the rear edge of plate D at the rear of the recess therein. Said coin will then fall clear down onto the hopper or chute. When the two slides of the double discharge device under the one or ten cent tubes 90 are drawn forward together, as is the case where the upper one is pulled out, the two coins contained in such slides are discharged, instead of only one, as described above. As soon as each slide is allowed to fly back into place under stress of the springs, another coin drops 95 down into the recess in it. The operation of the different slides, as several of them are actuated together from the same key-lever to make the amount of change indicated on the key, is 100 obvious from the description given above. If, for instance, the key marked 95 is pressed down, the upright lever-arm pulls on the cords or wires connected therewith and pulls out the discharge-slides under the fifty-cent, the twenty-five-cent, and the upper and lower slides 105 under the ten-cent coin holding tube. There are thereby discharged into the delivery-chute a fifty-cent, a twenty-five-cent, and two ten-cent pieces. The series of holes in the upright 110 arms allow of the attachment of the ends of different cords, so as to make the amount of throw that is necessary to draw out the slides to the proper extent. This is of advantage, as the cords run at different angles to different slides, though it is not necessary, for it is 115 not essential to the successful operation of my apparatus that all the slides should be pulled out to equal distances.

I contemplate, if desired, increasing the 120 number of key-levers and making proper connections between a number of them and various combinations of the one-cent slides and the discharge-slides of the other holders, so any one amount of change composed of combinations of cents with the other coins can be caused to be delivered by the motion of one lever or equivalent actuating device.

Having thus fully set forth the nature of my invention, what I claim is—

1. In a money-changing apparatus, in combination with the tubes adapted to hold coins of various denominations and provided with discharging-slides, a suitable actuating device 130

connected with and adapted to move two or more of such slides at a time, to cause the simultaneous delivery of several coins to make up a desired amount of change, substantially 5 as shown and described.

2. In a money-changing apparatus, in combination with the holders adapted to hold coins of different denominations and provided with discharging-slides, a series of suitable actuating devices, each connected with and adapted to move at once a different combination of two or more of the discharging-slides, to cause the delivery into a suitable hopper or chute of the different combination of coins, substantially 15 as and for the purpose described.

3. In a money-changer, in combination with the series of holders for coins of different denominations, provided with discharging-slides, a series of actuating devices composed of a 20 number of devices, each one of which is connected with and adapted to operate singly the discharging-slide of a different one of the holders, and others which are each severally connected with and adapted to operate a different 25 combination of two or more of slides to cause the delivery of a different one of the combinations of coins necessary to make up amounts of change not represented by any of the coins singly, substantially as shown and described.

30 4. In a money-changer, in combination with a series of holders adapted to receive and hold coins of different denominations and provided with discharging-slides, a lever connected by suitable connections with the discharging devices of two or more such coin-holders, all so arranged that by the movement of one lever two or more coins of different denominations will be delivered at once, substantially as shown and described.

40 5. In a money-changer, in combination with a series of holders for coins of different denominations, a series of actuating devices for the discharging-slides, consisting of a number of keys or levers, each of which is connected by 45 suitable connecting means with the discharging-slide of a different one of the coin-holders, and a number of keys or levers, each of which is connected by suitable connecting means with a different combination of two or more of the 50 discharging-slides, substantially as and for the purpose set forth.

6. In combination with a coin tube or holder, the discharging device for the same, adapted to cause the delivery of one or two of the 55 coins at will, and suitable actuating mechanism for the same, substantially as shown and described.

7. In combination with a coin tube or holder and suitable actuating devices, the two dis- 60 charge-slides, placed one above the other below the lower end thereof, so constructed and connected that the lower one can be drawn

out independently of the upper one, to discharge a single coin, but when the upper one is drawn out the lower one is caused to move 65 with it, so that the coins will be discharged by both slides, substantially as and for the purpose described.

8. In combination with the money-holding tube, the two discharging-slides, placed one above 70 the other below the end thereof, and provided with rigid arms or shanks, one of which is provided with a pin projecting through a slot in the other, all so constructed and arranged that the lower slide can be pulled out to discharge its coin without movement of the upper one, but when the latter is drawn out the other is caused to move with it, so that two coins will be discharged instead of one, substantially as shown and described. 80

9. In combination with the two slides, placed one above the other below the end of the money-holding tube, the shanks or arms attached thereto, the pin on the shank of the upper slide projecting through the slot in the shank 85 of the other, the springs engaging the shanks and tending to pull the slides back under the tube, a stop device to limit such backward movement of the slides, so that they shall normally rest with their openings below the bore of 90 the holder, and suitable actuating means connected with said slides to draw them out, substantially as and for the purpose described.

10. In a money-changer, the holders for the five, twenty-five, and fifty cent and for the 95 dollar coins, provided with single discharging-slides, and the holders for the one and ten cent coin, each provided with the two discharging-slides, so connected that the lower one can be moved independently of the upper, but 100 the latter carrying the lower slide with it when it is moved, in combination with a series of key-levers suitably marked or numbered, said series consisting of several levers, each one of which is connected with and adapted to actuate separately one of the slides of the five, twenty-five, and fifty cent and dollar holders, or one of the lower slides of the one and ten 105 cent holders, two levers, each connected with one of the upper slides of the latter holders, and a number of other levers, each connected with and adapted to operate a different combination of two or more of the discharging-slides of the five, ten, twenty-five, and fifty cent 110 coin holders to cause the delivery of a different combination of these coins to make up the amount of change indicated by the number on the key, substantially as shown and described. 115
